UNITED STATES PATENT OFFICE

BRADFORD W. DRAKE, OF STOUGHTON, MASSACHUSETTS

WOOL BAG OR THE LIKE

Application filed January 6, 1932. Serial No. 585,040.

It is customary to package wool for shipment in burlap bags, each bag being formed of a single piece folded, and stitched together with a cotton or jute strand about its marginal edges. In order to test the quality of the wool thus packaged it is customary to cut the strand at one side of the bag, and sometimes the bag itself becomes more or less cut in this operation, and then remove a sample of wool. Thereafter the cut portion of the bag is sewed together. During this procedure fragments of the strand, or of the bag itself, or both, are likely to become mixed into the wool and if proper care is not taken, these portions of foreign fiber pass with the wool through subsequent manufacturing operations and become inextricable therefrom. When the wool is manufactured into goods and is thereafter dyed, these foreign fibers do not take the dye exactly as the wool fibers do so that they become noticeable and detract materially from the market value of the goods.

The present invention has for an object to so construct the bag that it is unnecessary to cut the bag or sewing strand material to remove the sample, so that foreign fibers are not liable to become mixed into the wool during the sampling operation. To this end the sides and top of the bag are secured together by a wire and securing is effected in such manner that no cutting of either the bag itself or other parts is necessary to obtain access to the contents of the bag. The wire securing strand is therefore preferably engaged with elements of metal or other suitable material secured to the bag and from which the securing strand may be either loosened or detached when desired so that access may be had to the bag contents.

For a more complete understanding of this invention reference may be had to the accompanying drawing in which

Figure 1 is a perspective of a full bag secured by fastening means according to this invention.

Figure 2 is a fragmentary perspective showing the open bag itself, its contents being omitted, and showing the location of the wire securing elements.

Figure 3 is a fragmentary perspective showing the manner of closing and securing the mouth of the bag.

Figure 4 is a perspective of a wire securing element.

Figure 5 is a fragmentary perspective showing the element of Figure 4 secured to the bag.

Figure 6 is a rear elevation of a piece of the bag material to which an element such as shown in Figure 4 has been attached.

Figure 7 is a perspective of a different form of securing element.

Figure 8 is a detail section through a piece of the bag material showing an element such as shown in Figure 7 secured thereto.

Figure 9 is a fragmentary perspective of the securing wire.

Figure 10 is a view similar to Figure 5 but showing a slight modification.

Referring to the drawing, the bag, as shown best in Figure 2, is formed of a piece of burlap, or the like, as 1, having an open side 2 and an open top 3. The bottom is closed as by stitching shown at 4. Along opposite edges of the open side are fixed securing elements 5 arranged in staggered relation, starting from the lower edge of the bag and extending upwardly nearly to its top. Similar fastenings are applied to the bag spaced somewhat inwardly from its top, these also being in staggered relation as are the fasteners at the side. A wire, as shown in Figure 9 at 10, having one end formed with an enlarged portion to prevent it from being drawn up through the fasteners, as by forming a loop at 11 therein, is passed up from the lower edge of the open side engaging alternately with the fastening elements at opposite edges as shown in Figures 1 and 3, and the top of the bag is then folded over the contents, the bag material at the upper edge of the side 2 being brought together to form a "dog ear" 15 about which the wire is wound. The top edges of the bag being brought inwardly over the wool as shown in Figure 3, the top fasteners 5 are brought toward each other so that the wire 10 beyond the ear 15 may be passed alter-

nately back and forth across the top of the bag over to the opposite end thereof where the bag material may be gathered together into a second "dog ear" 16 about which the wire may be wrapped and tied and then its free end may be thrust into the wool therein, as shown at 17 in Figure 1, which prevents this end from becoming accidentally caught and unwound from the dog ear 16.

- 10 The fastening elements 5 are preferably formed as hooks as shown in Figures 4, 5 and 6, each having a base portion 20 from which project rearwardly extending securing prongs 21. The base portion 20 is extended on one end, the extension being brought back over the base to form the tongue 22 for the hook and between which and the outer face of the base portion 20 the wire may be moved to bring it into and out of engagement with the loop portion 23. This hook may be applied to the bag as shown best in Figure 6, the prongs 21 being passed therethrough and then clinched down against the inner face of the bag material.

15 20 25 Where the hooks are used for the fastening elements it is possible to draw the edges of the bag together sufficiently to permit the wire to be slipped out from a sufficient number of hooks to permit the bag to be opened along its side or top for the removal of material to be sampled. After this has been accomplished the wire may then be engaged with the hooks, thus closing up the opening made in the bag.

30 35 40 45 In place of hooks, however, the elements 5 may be eyes or eyelets as shown in Figures 7 and 8. The element may be formed of a wire 25 looped on itself and twisted together, its free ends 26 being passed through the bag material and bent into engagement with the inner face thereof as shown in Figure 8. Where eyelets or loops are used it will usually be necessary to detach the end portion 17 and unwind it from the dog ears to a sufficient extend to permit it to be pulled back through the fasteners to permit the opening to be made through the bag.

The hook element may, if desired, and as shown in Figure 10, be provided with a portion 28 struck up from the portion 20 toward the adjacent part of the tongue 22 to aid in preventing accidental disengagement of the bag securing wire 10 therefrom.

50 55 60 65 Another method of opening the bag is to cut the wire adjacent to the dog ear 15 and pull the wire below the cut out from engagement with the fastening elements for the desired distance after which the wire may be re-engaged with the fasteners and its free end twisted back on itself and thrust into the bag. This leaves one or two fasteners near the dog ear free from the wire but at this part of the bag this is unimportant, or substitute wires 65 may be used either for this short distance or

from the bottom of the bag continuously to and about the dog ear 15.

With any of the constructions described it will be apparent that the bag may be opened for sampling of its contents without requiring either the bag or any securing elements to be cut so that there is no danger of the introduction of foreign fibrous material either from the bag or from a securing strand into the wool contents.

75 80 85 90 95 From the foregoing description of certain embodiments of this invention it will be evident that various changes and modifications might be made without departing from the spirit or scope of this invention as defined by the appended claims.

I claim:

1. In combination, a fabric bag having an open side and top, fasteners secured to opposite edge portions of said open side and inwardly from the edges of said top, and a wire engaging said side and top fasteners and wrapped about dog ears at opposite sides of said top and holding said side and top closed.

through said top eyelets, wound around bag material at the other end of said top to form another dog ear, and having its free end thrust into the bag.

5 In testimony whereof I have affixed my signature.

BRADFORD W. DRAKE.
